UNITED STATES PATENT OFFICE.

RALPH S. PEIRCE, OF CHICAGO, ILLINOIS.

DOWEL-PIN FOR ELECTRICAL CONDUITS.

No. 825,069.

Specification of Letters Patent.

Patented July 3, 1906.

Application filed February 27, 1905. Serial No. 247,488.

To all whom it may concern:

Be it known that I, RALPH S. PEIRCE, a citizen of the United States of America, and a resident of Chicago, county of Cook, and State of Illinois, have invented a new and useful Improvement in Dowel-Pins for Electrical Conduits, of which the following is a specification.

My invention relates to an improvement in dowel-pins for securing the proper alinement between the several sections of material used in the building of underground electrical conduits.

A large portion of the underground conduits now in use is built of sections of tile having one or more ducts, this being of vitrified clay. The clay tile as delivered by the manufacturer is provided at each end with holes for dowel-pins, the holes in the ends of the adjoining sections being so located as to register with each other when the tile is in proper position. To secure the proper alinement during the laying of the tile, dowel-pins of various forms are used, these being inserted first into the holes of a piece of tile that has been laid in such manner that the protruding ends will enter the corresponding holes in the piece of tile being laid in such manner as to cause the proper registration of the duct or ducts within the tiles. The dowel-pins for this purpose have in the past been made of solid pieces of iron with a shoulder or projection about midway in their length to assure the dowel-pin projecting a proper distance into each section. In other cases wood pins have been used for this purpose. Both of these forms are objectionable for the following reasons: The solid iron dowel-pins are inflexible, and therefore when thrust or driven into a hole in the tile that is through some irregularity too small a cracking of the tile around the hole is caused, which either renders the tile unfit for use or at best roughens the wall of the duct to an undesirable degree. The holes in different tiles of the same lot or of different lots often vary in size, so that a number of different sizes of dowel-pins have to be carried in stock to assure proper fitting of the tiles together. Again, a solid iron pin of ordinary form and construction is liable to rust on account of the presence of moisture, and this in such cases has been found to cause such an expansion of the pins or of rust on the pins as to cause the subsequent breaking of the tile and injury of the duct. Still another objection to this form

of pin is that it is of considerable weight, which is objectionable in the matter of transportation, but more so in the handling in the trench. The wooden pins have the advantage of being cheap, but are subject to even greater objection in the point of expansion, due to the presence of moisture and to some extent due to excessive rigidity, which in the case of distorted dowel-holes or holes that are out of alinement may cause breakage of the tile. These objections on the part of the types of pins in use at the time of my invention are rendered all the more serious because of the fact that any breakage of the tile after setting which causes pieces of the inner wall of the ducts to break off and fall within the duct may cause the most serious damage to the cables subsequently to be carried in the duct, either in the drawing in or subsequent drawing out of the cable. Sharp pieces of hard burnt clay falling within a duct after a cable had been drawn in may easily render the subsequent withdrawal of the cable from the duct an impossibility or so greatly abrade the lead sheath in the process of withdrawal as to ruin the cable. It is to the remedy of these objectionable features that my present invention is directed.

My invention is illustrated in the accompanying sheet of drawings, in which—

Figure 1 is a perspective view of a single section of six-duct clay tile, showing one of my improved dowel-pins inserted and another about to be inserted in the two dowel-holes in the end of this section. Fig. 2 is a perspective view of a dowel-pin embodying my invention in its preferred form. Fig. 3 is a sectional view of the pin, taken on the line 3 of Fig. 2. Fig. 4 is a perspective view of a modified form of my invention, and Fig. 5 is a sectional view taken on the line 5 of Fig. 4.

As will be seen from the drawings, the dowel-pin embodying my invention is made in tubular form from a piece of sheet metal *a*, preferably iron rolled up from a flat sheet. The edges *b* and *c* of the sheet are in the preferred form (shown in Figs. 2 and 3) caused to overlap each other, so that if the tube is subjected to compressive stress it will yield and become smaller in diameter, the overlapping sections sliding by each other in an obvious manner. In this way the pin will adapt itself to almost any size of dowel-hole without causing such strain to come on the walls of the tile as to cause breakage. The ends of the tube are made somewhat smaller by

being tapered, as clearly shown at *d* and *e* in Fig. 3, thus facilitating the driving of the dowel-pins into holes of somewhat smaller than standard size and aiding the insertion of the tube into any size of hole.

About midway in the length of the tube is a projection *f*, preferably struck up from the metal before it is rolled into tubular form. This projection, which may be of any desired form, serves merely as a stop in the insertion of the pin into the tile, so as to assure the projection of the pin to about an equal distance in each of the abutting tiles.

The method of applying the dowel-pin to a standard piece of six-duct clay tile is clearly shown in Fig. 1, the pins being inserted into the holes, such as *g*, until the stop *f* engages the face of the tile, and from this it will be obvious that when the next section of the tile is laid in place the projection of the pins into the holes *g* of that section will, if those holes are properly located in the manufacture of the tile, cause the proper registration of the ducts *h* in the two sections, thus forming a continuous duct for the passage of the cables.

As the sections of the tiles are laid they are embedded in a mass of concrete, suitable and well known means being taken to prevent the entrance of concrete or mortar while in a plastic state through the interstices formed between the abutting edges of the tiles. When so laid and after the concrete has hardened, the conduit presents one continuous rigid structure, and it matters little whether or not the dowel-pins have any subsequent holding force. In fact, it may be stated that the function of the dowel-pin is to assure proper alinement during the laying of the tile and that if it rusts through and loses its strength in future no harm is done. For this reason the pins made in accordance with my invention may be of comparatively thin iron ungalvanized, and when so made are of comparatively cheap construction. Again, the pins are so light that a workman may carry a comparatively large number of them in his pocket during work, and this feature of lightness has an additional advantage in the matter of transportation.

The fact that dowel-pins made in accordance with my invention are not rigid as to their size adapts them readily to tile having dowel-holes differing in considerable degree as to diameter. Imperfectly-formed holes and holes slightly out of alinement may be used, since the pins may be driven in without danger of breakage to the duct material.

In Figs. 4 and 5 are shown a modified form

of my improved dowel-pin, the difference between this and the form shown in Figs. 2 and 3 being that the edges *b* and *c* of the metal do not overlap and, in fact, do not meet, considerable space being left between them. This provides for the contraction in the size of the tube in a manner that proves satisfactory in practice.

I do not wish to limit myself to the exact form of dowel-pin herein shown and described, as I consider that other forms of dowel-pins than those herein specifically illustrated having yielding sides would lie within the scope of my invention. For instance, a pin of corrugated sheet metal might be used to secure the proper degree of yielding when inserted in the dowel-holes. Neither do I wish to limit myself to dowel-pins to be used exclusively for the laying of clay tile, since the dowel-pin is obviously adaptable for similar purposes in other arts.

Having thus described my invention, what I claim as new, and desire to secure by Letters Patent, is—

1. As an article of manufacture, a tubular dowel-pin having tapered ends and having at a point in its middle length a lateral projection of a thickness to be negligible in the use of the dowel-pin, substantially as described.

2. As an article of manufacture, a sheet-metal dowel-pin having its ends tapered and having a projection struck up from the metal of said dowel-pin to limit its insertion.

3. As an article of manufacture, a sheet-metal dowel-pin for alining sections of tile, said dowel-pin having tapered ends and having at a point in its middle length a projection struck up from the sheet metal and of such small thickness as to produce not more than negligible separation of the tile ends, substantially as described.

4. As an article of manufacture, a dowel-pin for alining sections of tile, consisting of a sheet of metal rolled into tubular form, the adjacent edges of said sheet along the length of the tubular dowel-pin being movable with respect to each other, and a lateral projection being struck up from the sheet metal of said tube in the center of said dowel-pin for limiting its insertion, substantially as described.

Signed by me at Chicago, county of Cook, State of Illinois, in the presence of two witnesses.

RALPH S. PEIRCE.
